UNITED STATES PATENT OFFICE.

AUGUSTUS G. SNYDER, OF ILION, NEW YORK, ASSIGNOR TO WYCKOFF, SEAMANS & BENEDICT, OF ILION, NEW YORK, A CORPORATION OF NEW YORK.

COMBINED TELEGRAPHIC TRANSMITTER AND TYPE-WRITING MACHINE.

No. 904,157.

Specification of Letters Patent.

Patented Nov. 17, 1908.

Application filed April 8, 1904. Serial No. 202,177.

To all whom it may concern:

Be it known that I, AUGUSTUS G. SNYDER, a citizen of the United States, and resident of Ilion, in the county of Herkimer and State of New York, have invented certain new and useful Improvements in a Combined Telegraphic Transmitter and Type-Writing Machine, of which the following is a specification.

10 My invention relates to telegraphic transmitters and more especially to such transmitters combined with writing mechanism, and the object of my invention is to provide an improved device of this character.

15 My invention consists in certain parts, improvements and combinations which will be fully set forth herein and particularly pointed out in the claims.

In the accompanying drawings, Figure 1 is a view in elevation and in section of a machine embodying my invention, the section being taken substantially on the line *x—x* of Fig. 2. Fig. 2 is a plan view, the typewriter casing being shown in section above the key levers, and most of the casing of the transmitting device being removed. Fig. 3 is a view in vertical section on the line *y—y* of Fig. 2. Fig. 4 is a view in vertical section of a dash pot and its connections. Fig. 5 is a perspective view of the same. Fig. 6 is a face view of a certain comb plate used in my construction. Fig. 7 is a view of a part of my transmitter mechanism in rear elevation. Fig. 8 is a top plan view of the same. Fig. 9 is a front view of a portion of said mechanism. Fig. 10 is a view in section on the line *z—z* of Fig. 7. Figs. 11 and 12 are detail views of one of the stationary contact pieces. Fig. 13 is an end view of the parts shown in Fig. 9.

I have shown my transmitter combined with a front-strike typewriting machine in such a manner that when characters are written by said typewriting machine by operating the keys thereof in the ordinary way, telegraphic signals corresponding to the characters written will be transmitted over the line automatically. The particular form of typewriting mechanism here shown is not of my invention, and for most of the purposes of my invention any other suitable typewriting mechanism might be substituted therefor.

The typewriting machine here shown has a main frame which includes a base plate 1 (Fig. 1), supported by side plates 2 and a back end piece 3 (Fig. 2), the whole forming a sort of inclosure beneath the base plate. The key levers 4 extend beneath said base plate and are pivoted on a pivot rod or wire 5, supported in a slot in the face of a frame bar 6, which is supported by brackets 7 depending from the base-plate 1. Each of the key levers has an upwardly extending arm 8, the upper end of which is notched or slotted 60 to receive a pin 9 projecting from one side of a sub-lever 10, which is pivoted at 11 to a bar 12. The sub-levers 10 are connected by links 13 with type bars 14, which are pivotally mounted in hangers 15 so that the types 16 thereof are adapted to strike against the front plate of the platen 17, which is mounted upon the carriage 18 and is fed across the machine in the usual way. The key levers are returned to normal position by 75 springs 8', one of which is connected to each of the arms 8, and to a stationary part of the machine, as shown in Fig. 1.

The transmitting apparatus is mounted in the partially inclosed space beneath the base-plate 1 and has a framework which includes a base-plate 19 which extends nearly from one to the other of the side frame plates 2 of the typewriting machine, but does not touch said frame plates. The base-plate 19 rests on blocks 20 of insulating material to which it is secured by screws 21 (Fig. 2). Said blocks 20 are fastened to the side plates 2 by screws or bolts 22, as shown in Fig. 7. The base-plate 19 is thus insulated from the 90 framework of the typewriting machine. A front plate 23 rises from the base-plate 19. A post 24 (Figs. 3 and 8) rises from the base-plate 19 at each end of the apparatus, and each of said posts supports a frame bar 25 which is connected at its forward end to the front-plate 23. The two frame bars 25 are connected together near their rear ends by a cross bar 26 (Fig. 1) which completes the main frame of this portion of the apparatus. 95 Behind each of the posts 24 and between the frame bar 25 and the base-plate 19 there is mounted a rectangular piece of fiber or other insulating material 27.

As best shown in Figs. 7 and 8, a bracket 105 28 is fastened to the back edge of each of the

insulating blocks 27 by screws 29. As best shown in Fig. 8, each of the brackets 28 extends inward a short distance, and a plate of metal 30 is fastened to said brackets by 5 headed screws 31, which pass through slots 32 in the plate 30 near its ends, and are threaded into the brackets 28. The construction is such that the plate 30 may be moved a short distance to the right or left 10 and be secured in position by tightening the screws 31. The plate 30 has at its top and bottom edges forwardly projecting flanges 33 and 34, as best shown in Figs. 12 and 13. The plate 30, with its flanges 33 and 34, supports 15 a series of stationary contact pieces 35, which are secured in place on said plate by screws 36, which pass through openings in said plate and are threaded into said contact blocks. It will be perceived that any 20 one of the contact blocks may thus be readily removed without disturbing any other. Each of the stationary contact pieces 35 consists of a piece of metal having its front face cut away at intervals and the cut-away portions 25 filled with insulating material 37, as best shown in Figs. 11 and 12. The construction is such that if any conductor be drawn up or down across one of these contact pieces, it will be alternately in an electrical connection 30 with the plate 30 and insulated therefrom. The different stationary contact pieces have their metallic contact surfaces arranged in dots and dashes in accordance with the Morse alphabet, in a manner well known in 35 the art. It will be observed that the several stationary contact pieces are all in electrical contact with the plate 30, and that this plate is insulated from the framework of the transmitting apparatus by the insulating pieces 40 27. The movable contact pieces which co-operate with the stationary contact pieces 35 consist of a series of levers 38 (Figs. 1 and 3) having anti-friction rollers 39 on their free ends where they are pressed against the 45 stationary contact pieces.

As best shown in Figs. 2 and 3, the front plate 23 is formed with a series of slots 40 cut down from its upper edge, and the bottom of each of these slots forms a pivot for 50 one of the levers 38, it being cut-away and sharpened for the purpose, as shown in Fig. 3. Flat springs 41 secured to the front face of the front plate 23 by screws 42, bear against the front end of the levers 38 and 55 press the free ends of said levers into engagement with the stationary contact pieces. The levers 38 are guided near their free ends by a comb plate 43, which is formed at its ends with ears 44 which are secured to the 60 posts 24 by screws 45. As best shown in Fig. 2, two brackets 46 project inward from the front plate 23 and have threaded through them pivot screws 47, between which is pivoted a rock shaft 48 to which are secured by their hubs 49 the arms 50 of a uni- 65

versal bar 51 which extends beneath all of the levers 38. The shaft 48 has fixed thereto an arm 52 (Fig. 3) to which is pivoted a second arm 53, which rests in a notch formed by a bend in a flat spring 54, which extends around a stud 55 projecting from a bracket or lug 56, which rises from the base plate 19, and thence projects forwardly and rests on a set screw 57 threaded through the base plate 19. 75

The tension of the spring 54 may be regulated by adjusting the screw 57. In Fig. 1 the universal bar is shown in its highest position and in Fig. 3, in its lowest position; and by comparing these figures it will be seen that when the bar is in its highest position and the spring 54 is therefore in its most relaxed condition, the arm 53 stands at such an angle that the spring 54 acts upon the universal bar to a better mechanical advantage than it does when the universal bar is depressed and the spring is under greater compression. The arms 52 and 53 thus constitute a compensating device, whereby the effective force of the spring 54 is rendered approximately uniform throughout its stroke. The levers 38 normally stand in their upper position shown in Fig. 1, and they are returned to such position by the spring 54 acting on the universal bar in the manner which is being explained. The levers 38 are depressed by the key levers 4 of the typewriter machine through the instrumentality of a series of levers 58, which are pivoted at 59 to the frame bar 26. As best shown in Figs. 1 and 2, said frame bar is formed with a series of slots, one for each lever, and also with the slot 60 in its forward edge, and in this slot 60 the pivot rod or wire 59 is seated. Each of the levers 58 extends forward through one of the slots 40 of the front plate 23 and has formed on its lower edge a lug 61 which rests on the corresponding lever 38. The forward end of each of the levers 58 has pivoted thereto a link 62 which connects it with a sub-lever 63. Each of the links 62 is formed of two pieces of metal which do not touch, but which are joined together by a piece of insulating material 64 fastened to the two pieces of metal by rivets 65. By this means the levers 58 are insulated from the levers 63. The levers 63 are pivoted on a rod 66 fastened to a frame bar 67 which is secured to the back plate 3 of the typewriter frame. The levers 63 are drawn upward by springs 68 connected at one end to said levers and at the other end to a frame bar 69. The levers 63 are guided near their front ends and their upward motion is limited by a comb plate 70 (Figs. 1 and 2) which is secured at its ends to the side plates 2. The forward end of each of said levers 63 normally rests beneath a pin 71 projecting from one side of a link 72 which is pivoted at 73

to one of the key levers 4. It will be seen that the construction is such that upon the depression of a key lever the pin 71 will depress the corresponding lever 63, which 5 through its link 62 will depress the lever 58, and this in turn, by its lug 61, will depress the lever 38. Upon the release of the key, the key lever will be returned to normal position by its spring 8', the levers 63 and 10 58 will be returned to normal position by the spring 68, and the lever 38 will be returned to normal position by the spring 54 acting on the universal bar.

In order to regulate the speed of the 15 turn movement of the lever 38 I have provided a governor for the universal bar. A dash pot 75 is secured to the base plate 19 and, as best shown in Fig. 4, is provided with a piston 76, the piston rod 77 of which 20 is slotted at the top (Fig. 5) to receive an arm 78 to which it is pivoted by a pin 79. The arm 78 has a hub 80 which is fixed upon the shaft 48 and the other end of the arm is fixed at 81 (Fig. 2) to the universal bar 51. 25 It is desirable that the transmitting device shall interfere as little as possible with the depression of the key lever. Accordingly an air tube 82 has an opening on the inside of the dash pot beneath the piston 76 and a 30 ball valve 83 closes the upper end of said tube against the ingress of air, but readily allows the air to escape from beneath the piston. In order to prevent the ball from being blown entirely out of its seat, a bracket 35 84 is secured to the top of the dash pot and stands over the ball 83. When the universal bar is rising air is admitted to the dash pot through a duct 85 which opens into the dash pot beneath the piston, as shown in Fig. 4, 40 and which opens into the outside air through a conical opening 86 which is partially closed by the conical end of a rod 87 which is mounted in brackets 88 and 89 secured to the base plate 19.

45 The bracket 89 is slotted as shown at 90, and within said slot is mounted a nut 91 which is threaded on to the rod 87. Said nut 91 is formed into a gear 92, the teeth of which mesh with the teeth of a pinion 93, 50 which is fixed upon a shaft 94 which is journaled in the bracket 89. A disk or plate 95 is fastened to the outside of the frame plate 2 by screws 96 which are threaded into said plate 95 and which are insulated from 55 said frame plate 2 by washers and sleeves of insulating material, as shown in Fig. 2. A hollow shaft 97 is journaled in the plate 95 and passes through an opening in the side plate 2 which is larger than said shaft so 60 that the shaft does not touch the side plate. The shaft 94 enters an axial opening in the shaft 97 to which it is fixed by a set screw 98 which is threaded into the shaft 97 and engages the shaft 94. At its outer end the 65 shaft 97 is formed into or is provided with a

milled head 100. An arm 101 projects from a collar 102, which is fixed to the shaft 97 outside of the disk or plate 95. Between said disk or plate and said collar there is mounted upon said shaft an arm 103 of 70 spring metal, having at its free end a handle or button 104 and a pin projects inward from said arm and is adapted to enter one or another of a series of holes 105 formed in the disk or plate 95. The rod 87 is held 75 against rotation by a screw 106 which is threaded into the bracket 89 and enters a longitudinal slot 107 in said rod, as shown in Fig. 4. The construction is such that if the milled head 100 be turned, it will turn 80 the shaft 94 and pinion 93, which will turn the nut 91 and move the rod 87 into or out of the conical opening 86 in the dash pot. The pinion 93 is smaller than the gear 92 so that a very fine adjustment is afforded. 85 When the parts have been adjusted properly, the arm 103 is moved until the button 104 is in contact with the arm 101 and said arm 103 is held in position by its pin springing into one of the holes 105. The purpose 90 of this arrangement is as follows:—It is found that dust is liable to collect in the conical opening 86 and obstruct the opening so that, whenever the machine has been allowed to stand idle for a while it is necessary 95 to readjust the dash pot before it will give the proper speed. In order to prevent this, the proper adjustment is preserved by the arm 103, and when the operator has finished using the machine he turns the milled head 100 a considerable distance so as to withdraw 100 the rod 87 some distance out of the opening 86. The vent being thus left wide open is not so likely to collect dust as when it is left 105 in its operative adjustment with a fine crack between the walls of the vent and the conical end of the rod 87, and if any dust does collect it can be worked out by working the rod back and forth. The stop formed by the button 104 on the arm 103 enables the operator 110 to bring the rod 87 back to its original adjustment instantly and accurately.

It will be observed that in the operation of the machine the key levers are struck in the ordinary way for the purpose of writing on 115 the typewriting machine and that the depression of any key lever results in a simultaneous depression of its contact lever 38 and that the key lever is free to return to its normal position irrespective of the return 120 of the lever 38, and that the return of said lever 38 is controlled by the dash pot governor, which has been described.

According to the arrangement here adopted, the contact lever 38 is in engagement with the stationary contact piece 35, both on its down stroke and on its up stroke. I have therefore provided an independent circuit controller for breaking the telegraphic circuit when the lever is moving 130

downward and for closing the circuit when the lever is moving upward. A small metal plate 109 is secured to one of the insulating pieces 27 and an arm 110 is pivotally mounted 5 on a bolt 111 which passes through said arm and said plate 109 and through said insulating piece 27, on the outside of which it has threaded thereon a milled nut 112. A washer 113 of fiber or similar material is interposed between the head of the screw or bolt 111 and the arm 110. The construction is such that by loosening or tightening the milled nut 112 the arm 110 may be placed under any desired degree of frictional restraint. Such arm 110 extends in a forward direction and has formed in its forward end 10 a slot 114 into which projects a pin 115 secured to one of the arms 50 of the universal bar 51. The upper edge of the slot 114 is naked, but the lower edge is covered by a piece of insulating material 116. As the arm 110 is yieldingly held against motion in either direction by the friction washer 113, the pin 115 will press against the lower edge 15 of the slot when the universal bar is moving downward and against the upper edge of the slot when the universal bar is moving upward, and the universal bar will therefore be in electrical connection with the arm 110 when the universal bar is moving upward 20 and out of such connection when the universal bar is moving downward. The arm 110 is in electrical contact with the plate 109 which is connected by a conductor 117 with 25 a binding screw 118, which is in the telegraphic circuit. Said binding screw 118 and another binding screw 119 are mounted in a block of insulating material 120, as best shown in Fig. 7. The binding screw 119 is 30 connected by a conductor spring 121 with the plate 30, to which the stationary contact pieces are secured. It will thus be seen that the course of the current through the transmitting device will be from binding post 118, 35 conductor 117, plate 109, arm 110, pin 115, arm 50, universal bar 51, lever 38, roller 39, stationary contact piece 35, plate 30, spring 121, back to the binding post 119.

By an inspection of Fig. 2 it will be seen 40 that the rollers 39 are much narrower than the stationary contact pieces. I have provided means whereby the whole system of stationary contact pieces may be adjusted across the machine so as to bring a fresh portion 45 of each of the surfaces of said contact pieces under the said rollers in case the stationary contact pieces become worn. It is for this purpose that the openings 32, through which the headed screws 31 extend, are made 50 in the form of elongated slots, as shown in Fig. 7. Each of the brackets 28 is formed with a lug 122 through which is threaded a set screw 123, which may be secured in any position in which it has been adjusted by a 55 lock nut 124. The ends of the set screws

123 engage the ends of the plate 30 and afford a ready adjustment of said plate across the machine in the manner which has been described. As a guide to the operator in making this adjustment, the plate 30 is 60 cut away at one end, as shown at 125, making a notch or slot having beveled edges 126 on which are engraved index lines 127 which register with graduations 128 on one of the brackets 28. By observing the relation of 65 the index marks 127 and the graduations 128 the operator may adjust the position of the plate 30 with great nicety. After the plate has been adjusted the screws 31 are tightened and the plate is thus held in adjusted 70 position.

The spring 54 and its connections are necessarily so designed as to offer as little resistance as possible to the depression of the levers 38 in order that the telegraphic apparatus shall offer as little resistance as possible to the operation of the typewriter keys. The spring 54 and its connections are so designed as to press the universal bar upward 75 with only sufficient force to properly restore 80 the depressed lever 38. In case several typewriter keys were accidentally struck at the same time, thus depressing several of the rollers 38, the spring 54 would be unable to restore all of such levers and the transmitting apparatus would be thrown out of operation. I have therefore provided in the key board of the machine a supplemental or correction key 129, the lever 130 of which is pivoted on the rod 66 in the same manner 85 as the sublevers 63. As best shown in Figs. 1 and 2, the supplemental key lever 130 is normally drawn upward by one of the springs 68 and has projecting from its upper side, an arm 131 having projecting from its side 90 a pin 132 which extends over an arm 133, the hub 134 of which is fixed on the shaft 48, as by a pin 135 passing through said hub and shaft. The construction is such that in case the spring 54 is unable to return the 95 universal bar, the depression of the correction key will forcibly return said bar. As this key will generally be used for this purpose when more than one of the levers 38 are 100 depressed and as this key would usually return the levers with a greater speed than the spring 54, it is desirable that when it is operated the circuit shall be broken. To this end the binding post 119 is connected by a 105 conductor 136 with one member of a circuit controller which is controlled by the correction key. A bracket of insulating material 137 is secured to the back plate 3 of the typewriting machine, and a spring 138 (Fig. 1) is secured thereto by a screw 139 to which 110 the conductor 136 is connected. A conductor 140 which extends outside of the machine and to the line wire of the telegraphic circuit, is connected to a post 141, against which 115 the spring 138 is normally pressed by a piece 120

of insulating material 142, secured to the end of an arm 143 which projects upward from the lever 130, so that the circuit controller is normally closed; but when the correction key is depressed the arm 143 moves toward the front of the machine and the spring 138 is moved by its own resilience out of contact with the pin 141 and breaks the circuit. The key 129 may also be used in 5 case the operator observes that he has struck the wrong character key. If he has made this mistake he may hold the character key down and depress the correction key at the same time that he releases the character key. 10 In this way the circuit will be broken before the movable contact lever 38 moves upward across the face of the stationary contact piece 35, and the erroneous character will not be transmitted over the telegraph wire. 15 The upward motion of the levers 38 is limited by a plate 145 which lies above said levers, and this plate is so designed that normally each of the rollers 39 rests in engagement with one of the pieces of insulation 20 37, which are inserted in the contact pieces 35. It will be observed that the face of the contact pieces 35 is straight and that when the levers 38 are in their normal position they incline from their pivots slightly 25 upward. When any lever 38 is depressed it not only turns about the bottom of the slot 40 as a pivot, but slides a short distance forward through said slot, against the tension of the spring 41. This being the case the 30 springs 41 serve to hold in their normal elevated positions all of the levers 38 except the particular one which is forced down by the key levers. 35

The binding post 118 has connected there- 40 to a conductor 144 which passes outside of the machine and is connected to the line wire of the telegraph circuit. The conductors 140 and 144 are connected up in the telegraph circuit in exactly the same manner as the ordinary operator's key. The operator of this machine has at his side the usual relay and sounder, and he hears from the sounder the Morse signals which are automatically transmitted by the mechanism. 45 The Morse code consists of a succession of dots, dashes and spaces and the signals corresponding to different characters differ greatly in length, the letter "e" being represented by a signal dot and other characters 50 by combinations of dashes and dots, so that the signals corresponding to some of the other characters are several times as long as that which represents the letter "e." If the operator struck the typewriter keys at regular intervals of time, such an operation of the machine would result in irregular spaces being left between the different signals,—the spaces between short signals would be much longer than the spaces between long 55 signals. In order that a signal may be read-

ily interpreted by the receiving operator, it is necessary that the interval between characters shall be as nearly uniform as possible. In practice therefore the operator strikes the key and releases it, and as soon as he 70 hears the corresponding signal in his sounder he strikes the next key, striking the keys in such a way that the space between the letters shall be as nearly as possible uniform. In devices of this kind as heretofore constructed 75 it has been impossible to make this space uniform because the movable contact piece, which in the present case is the lever 38 and roller 39, has been required to move through a uniform distance, and has been controlled 80 in such movement by a governor. The result has been that those characters which are represented by a long combination of dots and dashes have occupied the entire stroke of the movable contact piece, whereas those 85 characters which are represented by shorter signals have occupied but a small portion of the stroke of the movable contact piece, the said contact piece moving for the greater part of the time across insulating material. 90 In order to remedy this defect in the present device I have made provision for moving the several levers 38 different distances corresponding to the respective lengths of the signals which such levers are designed to 95 transmit. The lever 38 corresponding to the letter "e" is depressed only far enough to form a single dot and other levers different distances in accordance with the lengths of their signals. To this end the comb plate 43 100 has its slots of different lengths, as shown in Fig. 6, so as to positively limit the length of the stroke of each of the levers 38. To the same end each of the levers 63 consists not of a single piece but of two pieces pivoted together at 146, as shown in Figs. 1, 2 and 3. The forward end piece 147 is bent to form a flange 148, into which are threaded two set screws 149 which engage the lower side of the lever 63 on opposite sides of the 110 pivot 146. These set screws are secured in adjusted position by lock nuts 150. By adjusting the set screws 149, the forward free end of the lever may be moved up or down, thus moving said end closer to or farther 115 from the pin 71. In this way any desired amount of lost motion may be secured between said pin 71 and the free end of the lever.

In the case of letters which are represented 120 by short signals the free ends of the levers are adjusted low so that the pin 71 does not strike the end of the lever 63 until the key has nearly reached the end of its downstroke, the lever 63 being thus moved but a short 125 distance. In the case of those characters which are represented by longer signals, the end of the lever is adjusted higher and is engaged by the pin 71 earlier in its stroke so that a long stroke is imparted to the lever 130

63 and consequently to the lever 38. The conductor surfaces, by which the signals are formed, are all arranged near the tops of the several contact blocks 35, so that the moment 5 the roller 39 has passed from the last conductor surface onto the insulation surface the parts are in their normal position, as shown in Fig. 1, ready for another depression of a character key and lever 38. If the 10 levers 38 all had the same length of stroke and the conducting surfaces of the short characters were near the bottom of the contact pieces 35, then when the signal had been transmitted the operator might be misled 15 into supposing that the parts had returned to normal position and he might then strike another key. In this way he would depress a second lever 38 before the first one had returned to normal position and the spring 54 20 might be unable to restore both levers. If, on the other hand, the levers 38 all had the same length of stroke, and if the contact surfaces of the characters represented by short signals were near the tops of the contact pieces 35, then when the "e" lever was 25 struck there would be added to the interval which the operator purposely left between this and the preceding character the length of time it would take the roller 39 to move 30 upward across the long stretch of insulating material until it reached the conductor surface which is designed to transmit the signal. The "e" would thus be separated from the preceding character for so long an interval 35 that the operator might be deceived into thinking that it belonged to another word.

It may sometimes be desirable to use the typewriting machine without using the transmitting device. To this end I have 40 provided means whereby the transmitting device may be thrown out of operative connection with the typewriter keys. Each of the links 72 is formed at its lower end with a longitudinal slot 152 and a rod 153 extends 45 through all of such slots and guides the links 72. The rod 153 is rigidly secured at its ends to arms 154 which are pivoted at 155 to the frame plates 2, the whole forming a swinging yoke frame. The rod 153 is extended at 50 one end, as shown in Fig. 2, outside of the casing where it is formed into a handle 156 by which the yoke-shaped frame may be swung toward the front or toward the back of the machine. In order to hold said frame 55 in one or another of its positions, a spring 157 which is secured to a lug 158 projecting from the side plate 2 has two notches 159 into one or another of which the rod 153 seats itself, according as said rod is in its 60 forward or in its rear position. When the rod 153 is in its rear position the pins 71 stand over the ends of the levers 63 and in position to engage the same; but when the rod 153 is drawn forward the links 72 swing 65 on their pivots and the pins 71 move for-

ward so that when the key levers are depressed said pins pass clear of the levers 63 and the transmitting device is inoperative.

The transmitting mechanism is protected 70 by a casing 160, 161 (Fig. 1).

What I claim as new and desire to secure by Letters Patent, is:—

1. The combination with typewriting mechanism including a series of keys, of an electric circuit; a series of stationary contact pieces and a series of reciprocatory contact pieces in said electric circuit for transmitting telegraphic signals, one reciprocatory contact piece for each key; and means for mechanically connecting the several reciprocatory contact pieces to or disconnecting them from said typewriter keys at will. 80

2. The combination with typewriting mechanism including a series of keys, of an electric circuit; a series of stationary contact pieces and a series of reciprocatory contact pieces in said electric circuit for transmitting telegraphic signals; means whereby said reciprocatory contact pieces are moved by the typewriter keys in one direction; 85 means for returning the typewriter keys; and independent means including a universal bar for returning said reciprocatory contact pieces. 90

3. The combination with typewriting 95 mechanism including a series of keys, of an electric circuit; a series of stationary contact pieces and a series of reciprocatory contact pieces in said electric circuit for transmitting telegraphic signals; means whereby 100 said reciprocatory contact pieces are moved by the typewriter keys in one direction; independent means including a universal bar for moving said reciprocatory contact pieces in the other direction; and a governor for 105 said universal bar.

4. The combination with typewriting mechanism including a series of keys and printing means operated thereby, of an electric circuit; a series of reciprocatory circuit 110 controllers for transmitting telegraphic signals; means whereby a reciprocatory circuit controller is moved in one direction upon the depression of a key; means for returning the depressed key; and independent 115 means including a spring actuated universal bar for returning the circuit controller.

5. The combination with typewriting mechanism including a series of keys and printing means controlled thereby, of an 120 electric circuit; a series of reciprocatory circuit controllers for transmitting telegraphic signals; means whereby a reciprocatory circuit controller is moved in one direction upon the depression of a key; means for returning the depressed key; independent 125 means including a spring actuated universal bar for returning the circuit controller; and means for regulating the speed of the return movement of said circuit controller. 130

6. The combination with typewriting mechanism including a series of keys and printing means controlled thereby, of an electric circuit; a series of fixed contact pieces and a series of reciprocatory contact pieces which coöperate to transmit telegraphic signals, there being one reciprocatory contact piece for each key; means for operatively connecting the several keys to said reciprocatory contact pieces; and means for disconnecting said keys from said reciprocatory contact pieces at will. 70
7. The combination with typewriting mechanism including a series of keys and printing means controlled thereby, of an electric circuit; a series of reciprocatory circuit controllers for transmitting telegraphic signals; means for moving a reciprocatory circuit controller in one direction upon the depression of a key; means for returning the depressed key; spring means for returning the circuit controller; and a supplemental key which is also operative to return said circuit controller. 75
8. The combination of a series of character keys; an electric circuit; a series of key controlled circuit controllers for transmitting telegraphic signals; and a supplemental key and a circuit controller controlled thereby, whereby the circuit may be broken and the transmission of the signal may be prevented, after a character key has been depressed. 80
9. The combination with typewriting mechanism including a series of character keys and printing means controlled thereby, of an electric circuit; a series of key controlled circuit controllers for transmitting telegraphic signals; a supplemental circuit controller; and a supplemental key in the key board of the typewriting mechanism for actuating said supplemental circuit controller, whereby the transmission of a signal may be prevented after a character key has been depressed. 85
10. The combination of a series of character keys; an electric circuit; a series of reciprocatory circuit controlling devices for transmitting telegraphic signals; means connecting the several character keys and circuit controllers whereby a circuit controller is moved in one direction by the depression of a key; spring means for returning such circuit controller; and a supplemental key which is also operative to return such circuit controller. 90
11. The combination of a series of character keys; an electric circuit; a series of reciprocatory circuit controlling devices for transmitting telegraphic signals; means connecting the several character keys and circuit controllers whereby a circuit controller is moved in one direction by the depression of a key; spring means for returning such circuit controller; a supplemental key which is also 95
- operative to return such circuit controller; and a supplemental circuit controller for breaking the circuit when said supplemental key is operated. 100
12. In a device for transmitting telegraphic signals, the combination of a series of stationary contact pieces and a series of coöperating movable contact pieces for transmitting telegraphic signals; and means for effecting an adjustment of one of said series of contact pieces as a whole with relation to the other in order to bring a fresh contact surface into use. 105
13. The combination of a series of keys having substantially equal strokes; an electric circuit; a series of circuit controllers for transmitting telegraphic signals, each circuit controller comprising a stationary contact piece and a key operated reciprocatory contact piece, and said reciprocatory contact pieces being moved different distances according to the lengths of the several signals. 110
14. The combination with the keys having substantially equal strokes and the key controlled printing means, of an electric circuit; a series of circuit controllers for transmitting telegraphic signals, each circuit controller comprising a stationary contact piece and a key operated reciprocatory contact piece, and means connecting each reciprocatory contact piece to its key, said means being adapted to impart to said contact piece an extent of motion appropriate to the length of the particular signal which such contact piece transmits. 115
15. The combination with the keys and the key controlled printing means, of an electric circuit; a series of circuit controllers for transmitting telegraphic signals, each circuit controller comprising a stationary contact piece and a key controlled reciprocatory contact piece; means whereby the several keys move their respective reciprocatory contact pieces different distances according to the lengths of the different signals; a universal bar for said reciprocatory contact pieces; means for moving said universal bar to restore any contact piece that has been moved by its key; and a governor for said universal bar. 120
16. In a transmitting device, the combination of a series of reciprocatory contact pieces for transmitting different telegraphic signals; keys having substantially equal strokes for operating said reciprocatory contact pieces; and means for limiting the extent of motion of each reciprocatory contact piece, said limiting means being adapted to allow to the different contact pieces different extents of motion according to the lengths of the different signals. 125
17. In a transmitting device, the combination of a series of movable contact pieces for transmitting different telegraphic signals; keys having substantially equal strokes for 130

operating said movable contact pieces; and means for limiting the extent of motion of each movable contact piece, said limiting means being adapted to allow to the different 5 contact pieces different extents of motion according to the lengths of the different signals.

18. The sub-lever 63, composed of two pieces rigidly connected together by a pivot and two set-screws, whereby the two pieces 10 may be adjusted, the one with relation to the other.

19. The combination of a series of key levers; a series of movable contact pieces for transmitting telegraphic signals; and connections 15 between said key levers and said movable contact pieces including a series of sub-levers, each composed of two pieces connected together by a pivot and two set screws, whereby one of said pieces may be adjusted with 20 relation to the other, so as to afford different extents of movement to said sub-levers and said movable contact pieces.

20. In a telegraphic transmitting device, the combination of a series of reciprocatory 25 contact pieces for transmitting telegraphic signals; a series of keys for moving said contact pieces in one direction; a universal bar for moving said contact pieces in the other direction; a spring for actuating said universal 30 bar; and a compensating device connecting said spring and said universal bar.

21. In a telegraphic transmitting device, the combination of a series of movable 35 contact pieces; means for moving said contact pieces; and a governor for said moving means comprising a dash pot having a vent 86, a rod 87 for regulating the opening in said vent, means for preventing rotation of said rod, a nut 91 threaded onto said rod, 40 and gearing for turning said nut.

22. In a telegraphic transmitting device, the combination of a series of stationary contact pieces; a series of levers 38; springs 41 for pressing said levers endwise thereof 45 against said stationary contact pieces; and means for moving said levers 38 to draw the ends thereof across the faces of said stationary contact pieces.

23. In a telegraphic transmitting device, 50 the combination of a series of stationary contact pieces; a series of levers 38, adapted to be moved across the faces of said stationary contact pieces; a series of levers 58 adapted to move said levers 38 in one direction; 55 spring means for moving said levers 38 in the other direction; and keys connected to said levers 58.

24. In a telegraphic transmitting device, 60 the combination of a plate or bar 30 of conducting material; a series of stationary contact pieces detachably secured to said bar; a series of movable contact pieces adapted to move across the faces of said stationary contact pieces; and means for adjusting said 65 bar to bring a fresh portion of the contact

surface of each of the stationary contact pieces into the path of the corresponding movable contact piece.

25. In a telegraphic transmitting device, the combination of a reciprocatory member; 70 and a frictionally restrained pivoted arm having a slot into which a portion of said reciprocatory member extends; one edge of said slot being of conducting and the other of non-conducting material; whereby said reciprocatory member is in electrical connection with said arm when moving in one direction and out of such connection when moving in the other direction.

26. In a writing and transmitting apparatus, 80 the combination of a series of keys having strokes of uniform length; types operated by said keys; and a series of reciprocatory contact pieces operated by said keys for transmitting telegraphic signals of different 85 lengths, said contact pieces moving through different distances according to the lengths of the several signals.

27. In a writing and transmitting apparatus, 90 the combination of a series of keys; a series of types operated by said keys; a series of reciprocatory contact pieces controlled by said keys for transmitting telegraphic signals of different lengths; and connections between said keys and said contact pieces, said connections having different 95 extents of lost motion whereby said contact pieces are moved different distances according to the respective lengths of the signals.

28. In a writing and transmitting apparatus, 100 the combination of a series of keys; types operated by said keys; a series of reciprocatory contact pieces controlled by said keys for transmitting telegraphic signals of different lengths; connections between said 105 keys and said contact pieces, said connections having different extents of lost motion whereby the contact pieces are moved different distances according to the lengths of the several signals; and stops for arresting said 110 contact pieces after different extents of motion.

29. In a transmitting apparatus, the combination of a series of stationary contact pieces, a series of reciprocatory contact 115 pieces and means for moving said reciprocatory contact pieces across the faces of said stationary contact pieces; each of said reciprocatory contact pieces consisting of a slidably pivoted lever one end of which engages 120 a stationary contact piece, said lever being spring pressed endwise toward said stationary contact piece.

Signed at Ilion, in the county of Herkimer and State of New York this sixth day 125 of April, A. D. 1904.

AUGUSTUS G. SNYDER.
